AUTOMATIC WATCH PART CLEANING
MACHINE

Otto Schurenberg, New York, N. Y.

Application August 27, 1948, Serial No. 46,495

15 Claims. (Cl. 134—58)

1

This invention relates to new and useful improvements in an automatic watch part cleaning machine. More particularly, the present invention constitutes an improvement of the watch part cleaning machine disclosed in my co-pending earlier application Serial No. 671,756 filed May 23, 1946.

That earlier application discloses an automatic machine in which the parts of a watch to be cleaned are placed in a basket which is automatically advanced from a starting position and then from one station to the next to first dip and whirl the basket containing the watch parts in a container of cleaning fluid, then in a container of rinsing fluid, then in a container of drying fluid, then in a heated drying container and then back to the starting position at which the watch parts can be removed from the container thoroughly cleaned and other watch parts to be cleaned can be placed in the basket and the cleaning cycle repeated.

The present invention relates to certain improvements in the electrical circuit which controls the lifting and lowering and turning of the basket from one station to the next, in the electrical circuit which controls spinning of the basket containing the watch parts being cleaned and in the mechanism for effecting the desired rotation of the basket from one station to the next between upward and downward movements thereof.

More specifically, the present invention relates to improved electrical circuits for the operation of the various parts of the machine which circuits are all so interconnected that their energization is controlled by a main switch but so arranged that all of the circuits are independent of each other for their intended purposes when the main switch has been moved to an on position.

Still further, the present invention proposes a circuit including a source of electrical energy, the main switch and a pilot light clearly visible at the front of the machine and arranged to be lit all the time the main switch is in its on position in a manner to clearly indicate that there is electric current in the machine.

Another object of the present invention proposes the provision of a lifting motor for lifting and lowering the basket containing the watch parts and for action in cooperation with a turning means for turning the basket from one station to the next when the basket is at the top of its stroke which electric motor is mounted in an electrical circuit including a timer having a nor-

2

mally closed switch which is arranged to be mechanically opened at the end of each down stroke of the basket in a manner to retain the basket within the containers for a preselected length of time.

The present invention further proposes the provision of a normally open micro-switch controlled by rotations of lifting motor and mounted in a circuit to the lifting motor which shunts the time controlled switch of the timer for momentarily closing the shunt circuit after the time controlled switch has been opened to insure stopping of the basket at the lowest point of each of its down strokes.

Still another object proposes the provision of a normally closed micro-switch mounted in the circuit to the lifting motor which includes the time controlled switch of the timer and which is arranged to be opened by a suitable cam portion as the machine finishes a complete operating cycle to stop the machine and prevent the automatic re-starting of another operating cycle.

A further object of the present invention proposes the provision of a further circuit to the electric motor which shunts the circuit which includes the timer and the normally closed micro-switch and which includes a manually operable two pole switch arranged in a manner to energize the lifting motor, notwithstanding that the normally closed micro-switch is being held open by its operating cam portion, to start an operating cycle of the machine to move the cam portion clear of the normally closed micro-switch permitting it to close so that further operations of the machine during one complete cycle may be controlled by the circuit which includes the normally closed micro-switch and the time controlled switch of the timer.

The present invention further proposes a spin motor for spinning the basket containing the watch parts to be cleaned and which motor is mounted in an electrical circuit including a normally open micro-switch controlled in a novel manner by one of the links of the mechanical lever arrangement which lifts and lowers the basket to spin the basket while in its lowered position in each of the containers and again while the basket is moving out of the containers and is at a position above the liquid level of the containers and while not moved clear of the top thereof to centrifugally throw all excess liquid from the watch parts and the basket.

A modification of the present invention proposes the provision of a novel mechanical means which is caused to operate by the mere act of

lifting and lowering the basket to turn the basket through an arc corresponding to the distance between adjacent stations in a manner to move the basket from one station to the next.

It is a further object of this invention to construct a watch part cleaning machine which is entirely automatic in operation to pass through a complete operating cycle when it has been set in operation, which is simple and durable and which can be manufactured and sold at a reasonable cost.

For further comprehension of the invention, and of the objects and advantages thereof, reference will be had to be following description and accompanying drawings, and to the appended claims in which the various novel features of the invention are more particularly set forth.

In the accompanying drawings forming a material part of this disclosure:

Fig. 1 is a front elevational view of the watch part cleaning machine constructed in accordance with the present invention.

Fig. 2 is a side elevational view of Fig. 1 looking from the left side thereof.

Fig. 3 is a horizontal sectional view of the machine taken on the line 3-3 of Fig. 2.

Fig. 4 is an enlarged view of the bottom portion of Fig. 2 with the left side of the cover removed, but with the parts in their lowered position.

Fig. 5 is a detailed view of a portion of Fig. 4 illustrating a different position of the parts.

Fig. 6 is a further detailed view of a portion of Fig. 4 illustrating still another position of the parts.

Fig. 7 is a horizontal sectional view taken on the line 7-7 of Fig. 4.

Fig. 8 is an enlarged broken vertical sectional view through the vertical post of the machine and taken on the line 8-8 of Fig. 2.

Fig. 9 is a horizontal sectional view taken on the line 9-9 of Fig. 8.

Fig. 10 is a horizontal sectional view taken on the line 10-10 of Fig. 8.

Fig. 11 is a horizontal sectional view taken on the line 11-11 of Fig. 8.

Fig. 12 is a partial horizontal sectional view taken on the line 12-12 of Fig. 4.

Fig. 13 is a partial horizontal sectional view taken on the line 13-13 of Fig. 3.

Fig. 14 is a schematic wiring diagram of the device.

Fig. 15 is a side elevational view similar to Fig. 2 but illustrating the machine constructed in accordance with a modification of the invention.

Fig. 16 is an enlarged detailed view of a portion of Fig. 15.

Fig. 17 is a horizontal sectional view taken on the line 17-17 of Fig. 16.

The watch part cleaning machine, according to the present invention, includes a hollow base 30 consisting of a flat bottom wall 31 and a bracket 32 mounted upon or integrally formed at the back of the bottom wall and overhanging a portion thereof. A panel 33 is attached to the front end of the bottom wall 31 and extends vertically therefrom. The hollow base 30 is completed by a cover 34 formed of separate sections which meet along a center line 35, see Figs. 1 and 3, which extends from the front to the rear of the base 30. The cover 34 is removably retained in position by means of screws 36 which pass through the cover 34 and which threadedly engage the adjacent portions of the bottom wall 31, the bracket 32 and the panel 33.

Extended vertically from the base 30, there is a fixedly mounted vertical post 37. As shown in Figs. 4 and 8, the bottom end of the vertical post 37 is extended into a boss 38 formed at the front end of the overhanging portion of the bracket 32 and is secured thereto by a set screw 39. The vertical post 37 is tubular in cross-section, see Figs. 8 to 10.

Mounted upon the top face of the cover 34 of the base 30 there are three liquid containers 40, 41 and 42 and a drying container 43. Each of the liquid containers 40, 41 and 42 is preferably formed of glass or some other transparent material and midway of their heights are provided with marks 44, see Figs. 1 and 2, designated "Liquid level" denoting the height to which the containers are to be filled with liquid. The bottoms of the liquid containers 40, 41 and 42 are retained within shallow receiving receptacles 45 securely mounted upon the top face of the cover 34. The drying container 43 comprises a tubular metal member securely mounted in position on the cover 34 concentric with an opening 46, see Fig. 13, formed in the respective section of the cover 34. At the front of the machine between the liquid container 40 and the drying container 43 there is a space which will be herein-after referred to as the starting and stopping space.

The liquid containers 40, 41 and 42 and the drying container 43 are evenly spaced with the starting and stopping space and arranged in a circle concentric with the tubular vertical post 37. Container 40 is to contain the cleaning fluid, container 41 a rinsing fluid and container 43 a drying fluid while the drying container is provided with a heater 47, which will be referred to in greater detail as this specification proceeds, for drying the watch parts prior to their removal from the machine.

Vertically slideable and rotatively mounted on the tubular vertical post 37 there is an outer tubular sleeve 48. Fixedly mounted by means of set screws 49 on the tubular sleeve 48 intermediate of its top and bottom ends, but closely adjacent the top end, there is a ring 50. A flat circular plate 51 is mounted concentrically on the sleeve 48 and extends radially in all directions therefrom. The plate 51 has its bottom face resting on the top face of the ring 50 and is secured thereto by several screws 52, see Fig. 8. Thus, the plate 51 moves vertically with the tubular sleeve 48 towards and away from the top ends of the containers 40, 41, 42 and 43.

The bottom face of the plate 51 is covered by a layer of soft rubber 53 and in the lowered or normal position of the plate 51, the layer of soft rubber 53 engages the open tops of the containers 40, 41 and 42 closing the same and preventing the loss of liquid by evaporation while the machine is standing idle or by evaporation and splashing while the machine is in operation. The top open ends of the containers 40, 41 and 42 are only open during the time the plate 51 is moving up and down. From Fig. 1 it will be clearly noted that the drying container 43 is somewhat shorter than the liquid containers 40, 41 and 42 so that in the normal or lowered position of the disc 51 the layer of soft rubber 53 will not engage and close the top of the drying container 43 permitting the heat from the drying container 43 to escape, thus preventing the portions of the layer of rubber which fall over the open top of the drying container 43 from being

75 cooked.

Mounted radially upon a portion of the top face of the plate 51 there is a spin motor 54 which has its driven shaft 55 extended through the plate 51 and provided at its bottom with an openable basket 56 into which the parts of the watch to be cleaned can be placed. A portion of the basket 56 is formed of wire mesh to permit a free passage of the liquid of the containers 40, 41 and 42 into the basket 56 and about the watch parts contained therein. Further details of the baskets 56 will not be given in this specification as they form no part of the present invention and as such baskets are generally known to those skilled in the art. Details of the operation of the spin motor 54 will be given later in this specification. It is apparent that as the plate 51 moves up and down that the spin motor 54 and the basket 56 will move therewith.

Above the plate 51, the tubular sleeve 48 is provided with five inwardly extending pins 57. The pins 57 are evenly spaced and have their inner ends projected into five evenly spaced flutes 58 formed in the vertical post 37 permitting vertical movement of the tubular sleeve 48 while restraining the sleeve 48 and parts carried thereby against rotational movement. At their top ends, the flutes 58 communicate with a reduced neck portion 49 formed about the vertical post 37. Upon upward movement of the tubular sleeve 48, the pins 57 move out of the top ends of the flutes 58 and into the reduced neck portion 59 freeing the plate 51 and the parts carried thereby for rotational movement relative to the fixedly mounted vertical post 37 and the containers 40, 41, 42 and 43.

Means is provided for lifting and lowering the tubular sleeve 48 and the parts carried thereby for extending the basket 56 into the containers 40, 41, 42 and 43 and for removing it from the containers. This means comprises an arm 60 which passes between the containers 41 and 42 and which has its rear end pivotally supported upon the top end of a bracket 61 by means of a pin 62. The bracket 61 is integrally formed with and extends vertically from the bracket 32, see Fig. 4. Between the containers 41 and 42, the arm 60 is formed with a downwardly offset portion which permits passage of the lower end of the basket 56 when moving from the container 41 to the container 42. The forward end of the arm 60 is bifurcated and extends about the tubular sleeve 48 concentric therewith.

Pivottally attached at their upper ends to the forward bifurcated end of the arm 60 there is a pair of depending links 63. The lower ends of the links 63 are pivotally attached to diametrically opposite sides of a collar 64 by means of pins 65. The lower end of the tubular sleeve 48 extends rotatively through the collar 64 which has its bottom face resting on the top face of a radial flange 66 integrally formed with the lower end of the tubular sleeve 48. The top face of the collar 64 is engaged by ball bearings 67 retained in position by means of a race 68 which is secured to the tubular sleeve 48 by one or more set screws 69. Thus, as the arm 60 is moved up and down about its pivot pin 62 the tubular sleeve 48 and the parts carried thereby will be similarly moved up and down on the vertical post 37.

A vertical link 70 has its upper end pivotally attached to the arm 66 closely adjacent its pivot pin 62 by means of a pin 71. An intermediate portion of the link 70 passes freely through an enlarged opening 72, see Figs. 4 and 7, formed in the overhanging portion of the bracket 32. The lower end of the vertical link 70 is pivotally at-

tached to the rear end of a horizontal lever 73 by means of a pivot pin 74. The lever 73 is pivotally supported intermediate of its ends by means of a pin 75 upon a depending portion 76 of the bracket 32.

Mounted upon the bottom wall 31 of the hollow base 30 adjacent one side of the front end of the lever 73 there is a lifting motor 77 which includes a gear reduction unit. The driven shaft 78 of the lifting motor 77 extends therefrom on the side adjacent the lever 73 and has fixedly mounted on the outer end thereof a radial arm 79. A stud 80 projects from the side of the radial arm 79 and engages an elongated slot 81 formed in the front end of the horizontal lever 73. Thus, as the driven shaft 78 is rotated by the lifting motor 77 the radial arm 79 will be rotated turning the stud 80 through a complete circle. As the stud 80 turns it will move back and forth in the length of the elongated slot 81 and pivot the lever 73 and move the link 70 up and down to in turn pivot the arm 60 up and down about its pivot pin 62 and raise and lower the tubular sleeve 48 and the parts carried thereby.

A counterbalance is provided for smoothing out the lifting and lowering of the tubular sleeve 48 under the influence of the lifting motor 77. This counterbalance comprises a contraction spring 82 which has one end anchored to the top end of a post 83 which extends from the bottom wall 31, by means of a screw 84. The rear end of the spring 82 is connected to one end of a cable 85 which extends over a pair of vertically spaced pulleys 86 rotatively supported on the bracket 32. The free end of the cable 85 depends from the topmost pulley 86 and is attached at its lower end to the back of the vertical link 70 slightly above the pivot pin 74, by means of a screw 87. The contraction spring 82 is always under slight tension so as to resist erratic movement of the tubular sleeve 48 and the linkage system interposed between the sleeve and the lifting motor 77 so that up and down movements of the sleeve 48 and the parts carried thereby will be smooth.

Several independent circuits are provided for controlling the energization of the lifting motor 77 in accordance with certain mechanical operations of the machine. In this connection it is pointed out that most wires for the various electrical parts have been omitted from the constructional details shown in Figs. 1 to 13; however, those electrical circuits are clearly shown in Fig. 14, the schematic wiring diagram of the device.

Referring to Fig. 14, it will be noted that the electrical circuits include the usual plug 88 adapted to be inserted into one of the usual electrical outlet receptacles or other source of electrical energy. One lead 89 from the plug 88 is connected to one contact of a toggle-type main switch 90 mounted on the panel 33 of the hollow base 30. The other contact of the main switch 90 is connected by means of a lead 91 with one contact of a pilot light 92. The other lead 93 from the plug 88 is connected to the other contact of the pilot light 92 so that the pilot light is connected in series with the source of electrical energy which causes the pilot light 92 to be lit when the toggle-type main switch 90 is closed to indicate that current is flowing in the machine.

Referring to Fig. 4 it will be noted that the pilot light 92 is fixedly mounted upon one arm of an L-shaped bracket 94 which has its other arm secured to the inside face of the panel 33. The panel 33 is provided with a hole in alignment with the pilot light and the hole is covered

by a piece of glass 94 through which rays of light from the pilot light 92 pass. The glass 94 is preferably tinted a red color as is generally known in the art to form a suitable warning signal that the main switch 90 is in an on position.

A lead 96 is connected to an intermediate portion of the lead 91 between the main switch 90 and the pilot 92 and has its other end connected to one of the outer poles 97 of a three pole two position starter switch 98. The starter switch 98 is also mounted on the panel 33 and has a manually depressible button 99 extended from the front face of the panel 33. The button 99 is normally in an extended position and completes the circuit to a timer 100 through a lead 101 which extends between one contact of the timer 100 and the center pole 102 of the starter switch 98. A lead 103 connects the other contact of the timer 100 with one contact of a normally closed micro-switch 104. The other contact of the micro-switch 104 is connected by a lead 105 to one contact of the lifting motor 77. A lead 106 connects the other contact of the lifting motor 77 with the lead 93 between the plug 88 and the pilot light 92 completing the normal operating circuit to the lifting motor 77.

The timer 100 is of a type generally known in the art and includes a clock mechanism (not shown) and a normally closed electrical switch (not shown). Means is interposed between the lifting motor 77 and the timer 100 for opening its normally closed switch and for setting the clock mechanism in operation to measure a predetermined length of time after which the normally closed switch of the timer 100 will again be closed for completing the circuit to the lifting motor 77. This all occurs while the plate 51 is in its lowered position and the basket 56 is lowered into one of the containers 40, 41, 42 or 43.

The means for operating the timer 100 comprises an arm 107, see Figs. 4 to 7, pivotally supported at its rear end to one side of the depending portion 76 of the bracket 32 upon the same pivot pin 75 which pivotally supports the horizontal lever 73. Intermediate of its ends the arm 107 is formed with an offset portion 108, see Fig. 7, which extends in the normal path of travel of the end of the stud 80 which projects beyond the side of the lever 73. As the stud moves in its orbit and approaches the end of each of its complete revolutions, its free end engages beneath the offset portion 108 of the arm 107 and raises the arm to the fully raised position shown in Fig. 5. Just before the stud 80 completes each of its complete revolutions, the extended end of the stud 80 moves clear of the offset portion 108 of the arm 107 and the arm drops, under the influence of gravity, back to its starting position as shown in Fig. 6.

A rod 109 projects laterally from the side of the end of the arm 107 and normally rests on the top of the casing of the timer 100, as clearly seen in Figs. 4 and 6. An operator stem 110 extends vertically slidably from the top of the casing of the timer 100 and freely slidably passes through a complementary hole 111 formed in the adjacent end of the rod 109. An enlarged head 112 is formed on the top end of the operator stem 110 preventing disengagement of the top end of the stem 110 from the hole 111 in the rod 109.

Assume that the tubular sleeve 48 is moving downwards on the vertical post 37 lowering the basket 56 into one of the containers 40, 41, 42 or 43, and that the stud 80 is about to complete one revolution from the position shown in Fig. 4. The

stud 80 then begins lifting the arm 107 which in turn raises the operator stem 110 of the timer 100. This upward movement of the operator stem 110 winds the spring of the clock mechanism 5 of the timer 100 and when these parts reach the fully up position shown in Fig. 5 the operator stem 110 will release the clock mechanism to snap the electric switch of the timer 100 from its normally closed position to an open position interrupting the supply of electrical current to the lifting motor stopping rotation of the stud, except for a shunt circuit which retains the motor 77 in operation for a moment longer to move the stud 80 clear of the offset portion 108 of the arm 107 freeing the arm 107 to drop back to the position shown in Fig. 6 with the operator stem 110 extending vertically above the rod 109. In the position of the parts shown in Fig. 6, the clock mechanism of the timer 100 will measure off the period of time from which it has been set and at the end of the period, the clock mechanism will snap the normally closed switch of the timer 100 back to its closed position to complete the circuit to the lifting motor 77 to energize the same for another complete revolution to raise and again lower the tubular sleeve 48 on the vertical post. At the same instant, the clock mechanism releases the operator stem 110 which drops under the influence of gravity back to the position shown in Fig. 4 stopping the operation of the clock mechanism until the operator stem 110 is again raised by the arm 107.

The shunt circuit referred to in the paragraph above functions to move the stud 80 to drop the offset portion 108 of the arm 107 and also insures stopping of the lifting motor 77 at the same point—the lowest possible point of movement of the plate 51 in which the layer of soft rubber 53 tightly seals the open tops of the liquid containers 40, 41 and 42 and in which the basket is extended completely into one of the containers 40, 41, 42 or 43 or at its lowest point in the starting and stopping space between the first liquid container 40 and the drying container 43.

That shunt circuit comprises a normally open micro-switch 113 fixedly mounted within the hollow base 30 immediately adjacent the path traversed by the free end of the radial arm 79 of the lifting motor 77, see Figs. 4 to 7. This normally open micro-switch 113 has a depressible plunger 114 adapted to be engaged by the free end of a spring member 115 secured to the casing of the micro-switch 113 below the plunger 114. The outer end of the radial arm 79 of the lifting motor 77 carries a tail member 116 which engages the spring member 115 and moves it to urge the plunger 114 in to close the normally open micro-switch 113 and hold the same closed until the tail member 116 moves clear of the free end 45 of the spring member 115. One contact of the micro-switch 113 is connected by a lead 117 to the lead 96 between the main switch 90 and the center pole 102 of the starter switch 98. The other contact of the micro-switch 113 is connected by a lead 118 to the lead 105, between the micro-switch 104 and the lift motor 77, to complete the circuit to the motor 77. Thus, when the normally open micro-switch 113 is closed by the tail member 116 of the radial arm 79 of the lift motor 77 rotation of the stud 80 will continue to move the stud clear of the offset portion 108 of the arm 107 and until the end of the tail member 116 moves clear of the spring member 115, in spite of the fact that the normally closed switch of the timer 100 is open. However, when

the tail member 116 moves clear of the spring member 115, as shown in Figs. 4 and 6, rotation of the lift motor 77 will be stopped as the normally closed switch of the timer 100 is open at this time and the lift motor 77 will remain out of operation until the normally closed switch of the timer 100 snaps back to its closed position and closes the circuit through the timer 100 to the lift motor 77.

A manually controllable means is provided for setting the timer for a pre-selected period of from one to seven minutes, as the period during which the normally closed switch of the timer 100 will be open and the circuit to the lift motor 77 will be broken and the plate 51 and the basket 56 will be in their lowered positions. This manually controllable means comprises a pivotally mounted lever 119 which extends from the casing of the timer 100. Within the casing, the lever 119 connects with the time adjustment mechanism of the clock mechanism to set the same for various pre-selected lengths of time as the lever 119 is pivoted up or down. A vertical stem 120 has its lower end connected to the front end of the lever 119 by means of a pivot pin 121. At its top end the stem 120 is pivotally connected by means of a pin 122 to the outer end of a lever 123 which is fixedly attached to and extends radially from the inner end of a stud shaft 124. The stud shaft 124 is rotatively extended through the panel 33 and is provided at its forward end with a control knob 125. The control knob 125 operates over a scale 126 numbered from "1" to "7" denoting various time intervals for which the timer 100 may be set by merely turning the knob 125. Further details of the timer 100 will not be given in this specification as its constructional details, beyond those already set forth in this specification, form no part of this invention and are generally known to those skilled in the electrical field.

The normally closed micro-switch 104 is mounted within the hollow base 30 on the front end of the overhanging portion of the bracket 32 by two screws 121, see Figs. 4 and 7. This micro-switch 104 includes a depressible plunger 128 which extends upwards through a hole in the cover 34 adjacent the bottom end of the fixedly mounted vertical post 37. The flange 66 on the bottom end of the tubular sleeve 48 is formed with an outwardly extending cam portion 66a. This cam portion 66a is formed on the side of the flange 66 adjacent the basket 56 to engage and depress the plunger 128 of the normally closed micro-switch 104 to open the same when the basket has left the drying container 43 and has reached its fully down position in the starting and stopping space between the containers 40 and 43. When the basket 56 reaches this down position in the starting and stopping space a complete cycle of the machine will have been completed and the opening of the normally closed micro-switch 104 will prevent the restarting of another complete cycle.

In this connection it is pointed out that at the end of each operating cycle, the timer 100 will be operated to open its normally closed electric switch and to set its clock mechanism in operation for measure of the period of time for which this timer has been set. However, the clock mechanism will merely harmlessly tick off the period of time for which it has been set and at the end of that period it will reclose its normally closed electric switch, but the circuit to the lifting motor 77 through the timer 100 will not go

into operation because the normally closed micro-switch will be held in its open position by the cam portion 66a of the flange 66, interrupting that circuit through the timer 100.

Normally, the manually depressible button 99 of the starter switch 98 is extended completing the circuit to the lift motor 77 through the timer 100. However, the button 99 may be pressed inwards to start an operating cycle of the machine by energizing the lift motor 77 to raise the sleeve 48 and move the cam portion 66a free of the depressible plunger 128 freeing the same to snap outwards and permit the normally closed micro-switch 104 to snap back to its normally closed position. To accomplish this the starter switch 98 has its other outside pole 129 connected to a lead 130 which in turn is connected to the lead 105 of the lift motor 77, between the lead 118 and the motor. Thus, when the manually depressible button 99 is pushed inwards it connects the lift motor 77 in an energizing circuit which includes in series the lead 89, the main switch 90, a portion of the lead 91, the lead 96, the center pole 102 of the starter switch 98, the outside pole 129, the lead 130, a portion of the lead 105, the lift motor 77 and the lead 106 back to the lead 93. The button 99 must be held depressed a sufficient length of time to permit a sufficient operation of the lift motor 77 to lift the tubular sleeve 48 a sufficient distance to completely disengage the cam portion 66a of the flange 66 from the depressible plunger 128 of the micro-switch 104 freeing the same to reclose itself. The button 99 is then released freeing the starter switch 98 which will then assume its other closed position closing the circuit through the timer 100 to control operation of the lift motor 77 at each of the operating stations of one complete operating cycle of the machine.

Mechanical means is provided which operates between each lifting and lowering of the tubular sleeve 48 on the vertical post 37 to turning the plate 51 and the parts carried thereby through one-fifth of a complete revolution which is the distance between adjacent operating stations of the machine. This mechanical means comprises five upwardly facing ratchet teeth 131 formed on the upper end of the tubular sleeve 48. A bushing 132 is fixedly mounted on the upper end of the vertical post 37 above the reduced neck portion 59 thereof. The bushing 132 is secured to the upper end of the vertical post 37 by several set screws 133. The bottom edge of the bushing 132 is formed with five downwardly facing ratchet teeth 134 arranged to be engaged by the ratchet teeth 131 of the tubular sleeve 48. With the pins 57 of the tubular sleeve 48 engaging the flutes 58 of the vertical post 37, the adjacent ends of the ratchet teeth 131 and 134 will be slightly disaligned, see Fig. 2. Thus, as the tubular sleeve 48 nearly reaches its fully up position, the pins 57 will move out of the top ends of the flutes 58 and into the reduced neck portion 59 freeing the sleeve 48 and the parts carried thereby for rotation relative to the vertical post 37. Simultaneously, the ratchet teeth 131 will begin to engage into the ratchet teeth 134 so that continued upward movement of the sleeve 48 will cause the ratchet teeth 131 and 134 to ride over one another until they reach their fully engaged positions in the complete up position of the tubular sleeve 48. However, since the teeth 131 and 134 were slightly disaligned when they started their engagement the teeth will only turn the plate 51 through the major portion of the one-

fifth revolution required to move the basket 56 from one operating station to the next.

The top end of the material of the vertical post 37 between adjacent flutes 58 is formed with downwardly sloping cam surfaces 135. Thus, when the tubular sleeve 48 begins to move downwards the ratchet teeth 131 of the sleeve 48 will move out of the ratchet teeth 134 of the bushing 132 and the pins 57 will move downwards through the reduced neck portion 59 of the vertical post 37. However, as the sleeve 48 was only moved through the major portion of the required one-fifth revolution the pins 57 will be disaligned with the flutes 58 and will engage and ride over the cam surfaces 135 which will turn the plate 51 and the parts carried thereby through the remaining portion of the one-fifth revolution aligning the pins 57 with the flutes 58 to move downward therein and also aligning the basket 56 concentrically with the next operating station. Also, this movement through the remaining portion of the one-fifth revolution will disalign the ratchet teeth 131 and 134 and condition these teeth for proper reengagement on the next upward movement of the sleeve 48. Movement of the plate 51 through the one-fifth revolution occurs while the basket 56 is disengaged from the containers and at a location above the top ends thereof.

The heater 47 which is cylindrical in form is supported concentrically beneath the tubular drying container 43 by a metallic strap 136, see Figs. 3 and 13, which has one end bent about the heater 47 and secured in position by a screw 131. The other end of the strap 136 is secured to the cover 34 outwards of the opening 46 by means of several nuts and bolts 138. The heater 47 is connected in series in a circuit which includes the main switch 90 so that the heater 47 will be energized when the main switch 90 is in an on position. This circuit comprises a lead 139 connected to the lead 96 which in turn connects with the lead 91 connected to the main switch 90 and which lead 139 has its other end connected to one side of the heater 47. A lead 140 is connected to the other side of the heater 47 and has its other end connected to the lead 106 which in turn connects with the lead 93. Thus, when the main switch 90 is turned on, the heater 47 will be energized to heat the interior of the drying container 43 to thoroughly dry the watch parts in the basket 56 while the basket is in its lowered position in the drying chamber 43.

Rotatively extended through the vertical post 37 there is a tube 141 the top end of which extends beyond the top end of the vertical post 37 and the adjacent end of the bushing 132. A flexible tube 142 has one end engaged over the extended top end of the tube 141 and is secured thereto by means of a collar 143 and set screws 144 which threadedly pass through the collar 143, through aligned openings formed in the end of the flexible tube 142 and bear against the sides of the tube 141. The other end of the flexible tube 142 is securely attached to the casing of the spin motor 54 about an opening (not shown) which connects the interior of the flexible tube with the interior of the motor casing. While the tube 142 is of flexible material it has sufficient rigidity to act as a drive connection between the spin motor 54 and the tube 141 to turn the tube 141 within the vertical post 37 to mimic all rotative movements of the tubular sleeve 48 and the parts carried thereby.

The lower end of the tube 141 carries an in-

sulation member 145 formed with spaced circular grooves 146. Within each of the grooves 146 there is fixedly mounted a collector ring 147 of conductive material. The insulation member 145 is formed with a tubular extension 145a extended into the bottom end of the tube 141 and secured thereto by a screw 148 so that the insulation member 145 will rotate with the tube 141.

A pair of electric leads 149 and 150 extend upwards through the tube 141 and through the flexible tube 142 and into the casing of the spin motor 54 and have their upper ends connected to the contacts of the spin motor 54. The lower ends of the leads 149 and 150 are each connected to one of the collector rings 147 by means of pins 151, see Fig. 8.

Mounted upon one side of the overhanging portion of the bracket 32 within the hollow base 30 there is a block of insulation material 151' securely held in position by several screws 152. Spaced brushes 153 of flexible conductive material are secured at their adjacent ends to the block of insulation material 151' by means of screws 154. The free ends of the brushes 153 extend into the grooves 146 of the insulation member 145 and make electrical contact with the collector rings 147. One of the brushes 153 is connected by a lead 155 to the lead 96 which connects with a portion of the lead 91 which in turn is connected to one of the contacts of the main switch 90. The other brush 153 is connected by a lead 156 to the lead 106 which in turn is connected to the lead 93. Connected in series in the lead 155 there is a normally open micro-switch 157 and a rheostat 158 for controlling the operation of the spin motor 54.

The micro-switch 157 is mounted with the hollow base 30 adjacent the path traversed by the lower end of the vertical link 10. The micro-switch 157 is provided with a depressible plunger 159 which is arranged to be pushed inwards for closing this normally open micro-switch 157. A flexible member 160 has its lower end fixedly attached to the casing of the micro-switch 157, its intermediate portion extended across the plunger 159 and is provided at its upper end with a roller 161. Thus, as the flexible member 160 is flexed towards the casing of the micro-switch 157 it will urge the plunger 159 in closing the switch 157 and completing the circuit to the spin motor 54.

Means is provided for flexing the flexible member 160 to close the micro-switch 157 while the basket 56 is in a lowered position in one of the containers 40, 41, 42 or 43 and again when the basket 56 is moving out of the containers and at a position between the "Liquid level" marks 44 and the tops of the containers, which is approximately the position shown in Fig. 2. This closing of the micro-switch energizes the spin motor 54 to spin the basket 56 while in the lowered position to thoroughly circulate the liquids of the containers 40, 41 and 42 through the basket and about the watch parts contained therein and to thoroughly circulate the heated air of the drying container 43 about the watch parts to dry the same. Again closing the micro-switch 157 while the basket is moving out of the containers and is above the "Liquid level" marks 44 causes all the excess accumulated liquid to be centrifugally thrown from the basket 56.

The means for flexing the flexible member 160 to close the micro-switch 157 in its lowered position comprises an L-shaped actuator 162 having one arm securely attached to the side of the

vertical link 70 and its other arm extended laterally from the side of the link 70 at a suitable elevation to engage the roller 161 and flex the flexible member 160 when the link 70 reaches its fully down position, as shown in Fig. 4. Rotatively mounted on the pin 74 which pivotally connects the adjacent ends of the vertical link 70 and the horizontal lever 73, there is a second actuator 163 having a forwardly extending detent 164 which is arranged to pass the roller 161 while the basket 56 is moving vertically into and out of the containers. The second actuator 163 is formed with a vertical pin 165 which has its top end normally disposed within the front end of an elongated slot 166 formed in the laterally extending arm of the L-shaped actuator 162, limiting rotative movement of the second actuator 163 to a rearward direction only. A light spring 167 has an intermediate portion wound about a pin 168 mounted on the laterally extending arm of the L-shaped actuator 162. One end of the spring 167 bent about the rear edge of that laterally extending arm of the L-shaped actuator 162 anchoring the same, and the other end of the spring 167 is disposed behind the pin 165 holding it within the front end of the elongated slot 166 and retaining the second actuator 163 in a rotative position in which its detent 164 will be operatively extended from the side of the actuator 163.

Assuming that the parts are in the position shown in Fig. 4 and that the lever 73 is pivoted to move the vertical link 70 upwards to move the basket 56 up and out of the container into which it is now engaged, as the link 70 starts its upward movement, the laterally extending arm of the L-shaped actuator 162 moves clear of the roller 161 and the micro-switch 157 immediately opens and the circuit to the spin motor 54 is interrupted and spinning of the basket 56 is stopped. As upward movement of the link 70 continues, the detent 164 of the second actuator 163 will engage the roller 161 and momentarily close the micro-switch 157 and energize the spin motor 54 to spin the basket 56 and centrifugally throw the excess liquid from the basket 56 while the basket is disposed above the "Liquid level" marks 44 of the containers but still within the top portion thereof. When the detent 164 moves clear of the roller 161 the micro-switch 157 will again snap to its open position interrupting the circuit to the spin motor 54. On upward movement of the link 70 the second actuator 163 is retained against rotating in a forward direction upon engaging the roller 161 by reason of the disposition of the pin 165 in the front end of the elongated slot 166. Upward movement of the link 70 continues until the fully up position is reached when both the actuators 162 and 163 are disposed above the roller 161. As the link 70 starts its downward movement to lower the basket 56 into the next container the detent 164 of the second actuator 163 is the first to engage the roller 161. However, this time the flexible member 160, which is stronger than the light spring 167, causes the second actuator 163 when the detent 164 engages the roller 161 to be rotated in a rearward direction against the holding action of the light spring 167 and the detent 164 will merely idle past the roller 161 without flexing the flexible member 160 to close the micro-switch 157 with the result that the spin motor 54 will not be

energized to spin the basket 56 while it is moving down into its respective container.

Downward movement of the vertical link 70 continues until the fully down position is again reached when the laterally extending arm of the L-shaped actuator will again engage the roller 161 and flex the flexible member 160 to close the micro-switch 54 and spin the basket 56 in its lowered position in its respective container.

10 Means is provided to prevent completion of the circuit to the spin motor 54 while the basket 56 is moving up and down in the starting and stopping space between the first container 40 and the drying container 43 and while the basket 56 is in its lowered position in that space. This means comprises non-conductive elements 169, see Figs. 8 and 11, mounted on superimposed sides of the collector rings 147 to be engaged by the brushes 153 while the tubular sleeve 48 and the tube 141 are in a rotative position with relation to the vertical post 37 in which the basket 56 is idle or moving vertically in the starting and stopping space. These non-conductive elements function to interrupt the circuit to the spin motor 54 notwithstanding that the main switch 90 and the micro-switch 157 are in their closed positions.

15 The rheostat 158 is connected in series in the lead 155 of the circuit of the spin motor 54 to control the R. P. M. of that motor. The rheostat 158 is mounted in position on the inner face of the panel 33 and has an operator stem 170 rotatively extended through the panel 33 and is provided with a control knob 171. The knob 171 operates over a calibrated scale 172 on the face of the panel 33 to indicate the R. P. M. at which the spin motor 54 is operating.

20 The operation of the machine is as follows:

25 With the machine in the starting position shown in Fig. 1, the operator first places the watch parts to be cleaned in the basket 56 and reassembles the basket with the driven shaft 55 of the spin motor 54. Then the main toggle-type switch 90 is turned to an on position to light the pilot light 92 and energize the heater 47. The operator then presses in on the button 99 of the starter switch 98 to energize the lift motor 71 to raise the tubular sleeve 48 and the parts carried thereby and to disengage the cam portion 66^a from the plunger 128 of the normally closed micro-switch 104 freeing that switch to snap to a closed position. When the cam portion 66^a has moved entirely clear of the plunger 128 the operator releases the button 99 of the starter switch 98 which will snap out and complete the circuit to the lift motor 71 through the timer 106. From this point on the operation of the machine is entirely operative. Rotation of the lift motor will now continue, but the spin motor 54 will not energize as the brushes 153 are now engaged with the non-conductive elements 169 of the collector rings 147.

30 As the tubular sleeve 48 reaches its fully up position, the pins 57 will move out of the flutes 58 with which they are engaged and into alignment with the reduced neck portion 59 of the vertical post 37. At the same instant the ratchet teeth 131 and 134 will begin to engage each other and turn the tubular sleeve 48 and the parts carried thereby through the major portion of the one-fifth revolution required to align the basket 56 with the first container 40. When the tubular sleeve 48 begins its downward movement the ratchet teeth 131 and 134 become disengaged and then the pins 57 engage the cam surfaces

135 and turn the tubular sleeve 48 through the remaining portion of the one-fifth revolution completing the alignment to the basket 56 with the first container 40. As downward movement of the tubular sleeve 48 continues the pins 57 reenter the flutes 58 and the detent 164 of the second actuator 163 idles past the roller 161 without closing the normally open micro-switch 157, so that the basket 56 is not spun by the spin motor 54.

As the tubular sleeve 48 nearly completes its downward movement on the vertical post 37, the stud 89 driven by the lift motor 77 will nearly complete one revolution and will engage the offset portion 108 of the arm 107 and lift the arm to draw upward on the operator stem 110 of the timer 100. When the operator stem 110 reaches its fully up position, in the fully up position of the adjacent end of the arm 107, the operator stem 110 will open the normally closed electric switch of the timer 100 and release the clock mechanism to tick off the period of time for which the timer 100 has been pre-set. This opening of the normally closed electric switch of the timer 100 interrupts the circuit to the lift motor 77 through the timer 100, however, the operation of the lift motor 77 does not immediately stop as the shunt circuit to the lift motor 77 through the normally open micro-switch 113 is retained closed by the tail portion 116 of the radial arm 79 of the lift motor 77. Rotation of the lift motor continues moving the stud 80 clear of the offset portion 108 freeing the arm 107 to drop back to its starting position shown in Fig. 6, and when the tail portion 116 moves clear of the spring member 115 of the micro-switch 113 the shunt circuit will be broken and rotation of the lift motor 77 will be instantly stopped. This occurs in the complete down position of the tubular sleeve 48 on the vertical post 37 and in which the basket 56 is completely extended into the first container 40.

In this completely down position of the parts, the laterally extending arm of the L-shaped actuator 162 engages the roller 161 and flexes the flexible member 160 to close the normally open micro-switch 157 completing the circuit to the spin motor 54 and energizing the spin motor 54 to spin the basket 56 in the liquid of the first container 40, all the time the parts are in their down position.

When the timer 100 completes the time for which it has been set it immediately releases its operator stem 110 which is drawn downward from the position shown in Fig. 6 to that shown in Fig. 4 and acts to again close the normally closed electrical switch of the timer 100 completing the circuit to the lift motor 77 to again lift the tubular sleeve 48 on the vertical post 37 and start the withdrawal of the basket 56 from the first container 40. Immediately, the laterally extending arm of the L-shaped actuator 162 moves clear of the roller 161 freeing the micro-switch 157 to assume its normally open position interrupting the circuit to the spin motor 54 and stopping spinning of the basket 56.

As upward movement of the tubular sleeve 48 continues, the detent 164 of the second actuator 163 engages the roller 161 and momentarily flexes the flexible member 160 to close the normally open micro-switch 157 to momentarily close the circuit to the spin motor 54 to spin the basket 56 while still within the first container 40 but while in a position slightly above the "Liquid level" mark 44 to centrifugally throw all excess liquid

from the basket 56. As upward movement continues, the detent 164 moves clear of the roller 161 and micro-switch 157 again snaps to its normally open position disrupting the circuit to the spin motor 54 stopping rotations of the basket 56.

When the fully up position of the tubular sleeve 48 is again reached, the ratchet teeth 131 and 134 and related parts will again function to turn the sleeve 48 and the parts carried thereby through a second one-fifth of a revolution required to turn the basket 56 from its axially aligned position with the first container 40 into its axially aligned position with the second container 41. The down and up movements described in connection with the first container 40 is then repeated for the second container 41, for the drying container 43; however, in the drying container 43, the basket 56 is not submerged into any liquid but its spinning is effected in the drying container 43 to thoroughly circulate the heated air of that chamber about the watch parts in the basket 56.

When the basket moves out of the drying chamber 43 and starts its final downward movement in the starting and stopping space between the first container 40 and the drying container 43, the non-conductive elements 169 of the collector rings 147 will have been turned through one complete revolution to be engaged by the adjacent ends of the brushes 153 to interrupt the circuit to the spin motor 54 and prevent the energization of that motor notwithstanding the closing of the normally open micro-switch 157 when the sleeve 48 reaches its fully down position in that starting and stopping space.

When the tubular sleeve 48 reaches its fully down position with the basket in the starting and stopping space, the cam portion 66^a will re-engage the plunger 128 of the normally closed micro-switch 104 and open the same and interrupt the circuit to the lift motor 77 and the lift motor will again be deenergized when the tail portion 116 again releases the spring member 115 of the normally open micro-switch 113 freeing that switch to assume its normally open position shutting off the lift motor 77. During this downward movement of the basket in the starting position, the arm 107 was again raised by the stud 80 to lift the operator stem 110 of the timer 100 to set the clock mechanism in operation and open the normally closed switch of that timer. However, the timer will merely tick off the period for which it has been set and at the end of that period reclose its normally closed switch but the circuit to the lift motor 77 through the timer 100 is not completed as the micro-switch 104 is being held in its open position by the cam portion 66^a.

In this fully down position of the basket 56 in the starting space the basket 56 can be removed and the watch parts taken therefrom. Additional parts to be cleaned may then be placed in the basket and the basket reconnected with the driven shaft 55 of the spin motor 54 and another complete cycle of the machine started by again pressing on the button 99 of the starter switch 98.

The period for which the timer 100 is set may be adjusted by turning its control knob 125 and the R. P. M. of the spin motor 54 may be varied by turning the control 171 of the rheostat 158.

In the modification of the watch part cleaning machine illustrated in Figs. 15 to 17 the construction of the machine is similar to that previously described differing only in the means for

effecting the required one-fifth revolution of the tubular member 48' to move the basket 56 from its aligned position with one container into its aligned position with the next container.

In this modification of the invention, the bushing 132' is axially slidably and rotatively mounted on the upper end of the vertical post 37 above the reduced neck portion 59. Movements of the bushing 132' are limited by a radially inwardly extending pin 173 which engages into a complementary upwardly inclined groove 174 formed in the side of the vertical post 37. The bushing 132' is resiliently urged into a lowered position by an expansion spring 175 concentric with the vertical post 37 and which operates between the adjacent ends of the bushing 132' and the collar 143.

The bottom edge of the bushing 132' is formed with ratchet teeth 134' in vertical alignment with complementary teeth 131' formed on the top end of the tubular sleeve 48'.

With this modified form of turning means, this watch part cleaning machine operates as follows:

As the sleeve 48' nears the completion of its upward stroke, the pins 57 will move out of the top ends of the flutes 58 and at substantially the same time, the ratchet teeth 131' and 134' will become completely engaged. As further upward movement of the sleeve 48' continues it will cause upward movement of the bushing 132' against the holding action of the spring 175 and the pin 173 riding in the groove 174 will cause rotation of the bushing 132' and in turn the tubular sleeve 48' due to the interengagement of the ratchet teeth 131' and 134'. The groove 174 is of a length to effect nearly a complete one-fifth revolution of the tubular sleeve 48' and the parts carried thereby by the time the pin 173 reaches the top end of the groove 174. As the sleeve 48' reverses itself and starts its downward movement the pins 57 will engage the cam surfaces 135 and effect a rotation of the sleeve 48' through the remaining portion of the one-fifth revolution before the pins 57 reenter the flutes 58 as downward movement of the sleeve 48' continues. If the groove 174 is made of a length to effect the entire one-fifth revolution of the sleeve 48' and the parts carried thereby, then the cam surfaces 135 will merely act as guides insuring a proper reengagement of the pins 57 with the flutes 58.

In other constructional respects and in other phases of operation this modified form of the invention is similar to the first form of the invention and like reference numerals are used to identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lower-

ing said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its full raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electric switch, and a circuit connecting said source of electrical energy, said main switch, the switch of said timer and said lift motor in series to energize said lift motor to raise and lower said sleeve when said switches are closed.

2. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lowering said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its full raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electric switch, and a circuit connecting said source of electrical energy, said main switch, the switch of said timer and said lift motor in series to energize said lift motor to raise and lower said sleeve when said switches are closed, and means for opening the normally closed switch of said timer and for setting said timer in operation to measure a pre-selected period of time when said sleeve is in its lowered position at the end of which period of time said timer recloses its switch to reenergize said lift motor to raise said sleeve.

3. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lowering said sleeve, a circular plate mounted concentrically on said sleeve adjacent the top end thereof and arranged to engage over and close the open tops of cer-

tain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its full raised position and again moving away therefrom for turning said sleeve through that portion of a complete revolution corresponding to the spacing of said containers to shift said basket from axial alignment with one container into an axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, and a normally closed micro-switch connected in series in said circuit, and a projecting cam portion on the lower end of said sleeve for opening said micro-switch when said sleeve moves downwards with said basket in the starting and stopping space following a complete operating cycle of the machine to open said micro-switch and shut off said machine, said micro-switch including a depressible actuator button and mounted on said hollow base to have its button engaged by said cam portion as said sleeve moves downward on said post at the end of the operating cycle.

4. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lowering said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its full raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, and a normally closed micro-switch connected in series in said circuit, and a projecting cam portion on the lower end of said sleeve for opening said micro-switch when said sleeve moves downwards with said basket in the starting and stopping space following a complete operating cycle of the machine to open said micro-switch and shut off said machine, said micro-switch including a depressible actuator button and mounted on said hollow base to have its button engaged by said cam portion as said sleeve moves downward on said post at the end of the operating cycle.

including a depressible actuator button and mounted on said hollow base to have its button engaged by said cam portion as said sleeve moves downward on said post at the end of the operating cycle, and a manually operable starter switch, and a second circuit connecting said source of electrical energy, said main switch, said starter switch and said lift motor in series, whereby said starter switch may be operated to close said second circuit to energize said motor to lift said sleeve and disengage said cam portion from said manually closed micro-switch freeing the same to assume its normally closed position when starting the machine on an operating cycle.

5. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lowering said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its full raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, and a normally closed micro-switch connected in series in said circuit, and a projecting cam portion on the lower end of said sleeve for opening said micro-switch when said sleeve moves downwards with said basket in the starting and stopping space following a complete operating cycle of the machine to open said micro-switch and shut off said machine, said micro-switch including a depressible actuator button and mounted on said hollow base to have its button engaged by said cam portion as said sleeve moves downward on said post at the end of the operating cycle, a normally open micro-switch connected in parallel in said circuit shunting said timer and said normally closed micro-switch, a radial arm on the driven shaft of said lift motor which makes one complete revolution for each 60 up and down movement of said sleeve, and a tail portion on the outer end of said radial arm for engaging and momentarily closing said normally open micro-switch as said radial arm completes one revolution and the normally closed switch of said timer is opened to insure stopping of said lift motor always at the complete lowered position of said sleeve.

6. In a watch cleaning machine having a hollow base and a vertical post extending centrally therefrom and a series of evenly spaced contain-

ers and a starting and stopping space between the first and last containers arranged in a circle about the vertical post, a tubular sleeve vertically slidable on the vertical post, means operated by a lift motor for raising and lowering said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its full raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, a heater for one of said containers, and a second circuit connecting said heater in series with said source of electrical energy and said main switch to cause said heater to be energized when said main switch is moved to an on position.

7. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, an arm pivotally mounted at one end of a bracket extending upward from said hollow base and having its other end pivotally connected to said sleeve, a vertical link having its top end connected to said arm intermediate of its ends and its lower end extended into said base, means within said base operated by a lift motor and connected to the bottom end of said link to raise and lower said link to pivot said arm and in turn raise and lower said sleeve on said post, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its fully raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, a normally open micro-switch, a second circuit connecting in series said source of electrical energy, said main switch, the switch of said timer and said lift motor in series to energize said lift motor to raise and lower said sleeve when said switches are closed, a normally open micro-switch, said normally open micro-switch and said spin motor for energizing said spin motor to rotate said bracket when said normally open micro-switch is closed, and means on said vertically movable link for closing said normally open micro-switch in the lowered position of said link and for again closing said normally open micro-switch as said link is moving upwards.

lower said sleeve when said switches are closed, a normally open micro-switch, a second circuit connecting in series said source of electrical energy, said main switch, said normally open micro-switch and said spin motor for energizing said spin motor to rotate said bracket when said normally open micro-switch is closed, and means on said vertically movable link for closing said normally open micro-switch in the lowered position of said link and for again closing said normally open micro-switch as said link is moving upwards.

8. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, an arm pivotally mounted at one end of a bracket extending upward from said hollow base and having its other end pivotally connected to said sleeve, a vertical link having its top end connected to said arm intermediate of its ends and its lower end extended into said base, means within said base operated by a lift motor and connected to the bottom end of said link to raise and lower said link to pivot said arm and in turn raise and lower said sleeve on said post, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its fully raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, a normally open micro-switch, a second circuit connecting in series said source of electrical energy, said main switch, the switch of said timer and said lift motor in series to energize said lift motor to raise and lower said sleeve when said switches are closed, a normally open micro-switch, said normally open micro-switch and said spin motor for energizing said spin motor to rotate said bracket when said normally open micro-switch is closed, and means on said vertically movable link for closing said normally open micro-switch in the lowered position of said link and for again closing said normally open micro-switch as said link is moving upwards, said closing means comprises an actuator mounted on said link to engage said micro-switch in the lowered position of said link, and a second actuator mounted on said link below said actuator to engage and close said micro-switch on upward movement of said link but to idle over said micro-switch on downward movement of said link.

9. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, an arm pivotally mounted at one end of a bracket extending upward from said hollow base and having its other end pivotally connected to said sleeve, a vertical link having its top end connected to said arm intermediate of its ends and its lower end extended into said base, means within said base operated by a lift motor and connected to the bottom end of said link to raise and lower said link to pivot said arm and in turn raise and lower said sleeve on said post, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its fully raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, a normally open micro-switch, a second circuit connecting in series said source of electrical energy, said main switch, the switch of said timer and said lift motor in series to energize said lift motor to raise and lower said sleeve when said switches are closed, a normally open micro-switch, said normally open micro-switch and said spin motor for energizing said spin motor to rotate said bracket when said normally open micro-switch is closed, and means on said vertically movable link for closing said normally open micro-switch in the lowered position of said link and for again closing said normally open micro-switch as said link is moving upwards.

about the vertical post, a tubular sleeve vertically slideable on the vertical post, an arm pivotally mounted at one end of a bracket extending upward from said hollow base and having its other end pivotally connected to said sleeve, a vertical link having its top end connected to said arm intermediate of its ends and its lower end extended into said base, means within said base operated by a lift motor and connected to the bottom end of said link to raise and lower said link to pivot said arm and in turn raise and lower said sleeve on said post, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its fully raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, a normally open micro-switch, a second circuit connecting in series said source of electrical energy, said main switch, said normally open micro-switch and said spin motor for energizing said spin motor to rotate said bracket when said normally open micro-switch is closed, and means on said vertically movable link for closing said normally open micro-switch in the lowered position of said link and for again closing said normally open micro-switch as said link is moving upwards, a tube extended rotatively through the tubular vertical post, a flexible tube connecting the top end of said tube with the casing of said spin motor to cause rotation of said tube within the vertical post, an insulation member mounted on the lower end of said tube and formed with vertically spaced circular grooves, conductive collector rings mounted in said grooves, leads of said second circuit connecting said collector rings to said spin motor, and fixedly mounted brushes connected in said second circuit and having free ends engaging said collector rings for conveying electrical current to said rings in all rotative positions of said tubes.

10. In a watch cleaning machine having a hollow base and a vertical post extending centrally therefrom and a series of evenly spaced containers and a starting and stopping space between the first and last containers arranged in a circle about the vertical post, a tubular sleeve vertically slideable on the vertical post, an arm pivotally mounted at one end of a bracket extending upward from said hollow base and having its other end pivotally connected to said sleeve, a vertical link having its top end connected to said arm intermediate of its ends and its lower end extended into said base, means within said base operated by a lift motor and

connected to the bottom end of said link to raise and lower said link to pivot said arm and in turn raise and lower said sleeve on said post, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its fully raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, a normally open micro-switch, a second circuit connecting in series said source of electrical energy, said main switch, said normally open micro-switch and said spin motor for energizing said spin motor to rotate said bracket when said normally open micro-switch is closed, and means on said vertically movable link for closing said normally open micro-switch in the lowered position of said link and for again closing said normally open micro-switch as said link is moving upwards, a tube extended rotatively through the tubular vertical post, a flexible tube connecting the top end of said tube with the casing of said spin motor to cause rotation of said tube within the vertical post, an insulation member mounted on the lower end of said tube and formed with vertically spaced circular grooves, conductive collector rings mounted in said grooves, leads of said second circuit connecting said collector rings to said spin motor, and fixedly mounted brushes connected in said second circuit and having free ends engaging said collector rings for conveying electrical current to said rings in all rotative positions of said tubes, and non-conductive elements mounted on adjacent sides of said collector rings to be engaged by said brushes to prevent completion of said second circuit to said spin motor while said basket is moving vertically or is in a lowered position in the starting and stopping space.

11. In a watch cleaning machine having a hollow base and a vertical post extending centrally therefrom and a series of evenly spaced containers and a starting and stopping space between the first and last containers arranged in a circle about the vertical post, a tubular sleeve vertically slideable on the vertical post, means operated by a lift motor for raising and lowering said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and

lowered positions of said sleeve, means on said sleeve and the vertical post effective while said sleeve is approaching its fully raised position for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, said means for turning said sleeve, comprising ratchet teeth formed on the upper end of said sleeve, a bushing vertically movable and rotatively mounted on the vertical post, means retaining said bushing in a lowered position, means for causing said bushing to be rotated through a portion of a revolution substantially equal to the distance between adjacent containers while the bushing is moving upwards, and ratchet teeth on the lower edge of said bushing to be engaged by the ratchet teeth of said sleeve as said sleeve approaches its fully up position after which further upward movement of said sleeve will cause said bushing to be raised with a turning motion to turn said sleeve.

12. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lowering said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its fully raised position for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, said means for turning said sleeve, comprising ratchet teeth formed on the upper end of said sleeve, a bushing vertically movable and rotatively mounted on the vertical post, means retaining said bushing in a lowered position, means for causing said bushing to be rotated through a portion of a revolution substantially equal to the distance between adjacent containers while the bushing is moving upwards, and ratchet teeth on the lower edge of said bushing to be engaged by the ratchet teeth of said sleeve as said sleeve approaches its fully up position after which further upward movement of said sleeve will cause said bushing to be raised with a turning motion to turn said sleeve, said bushing rotating means comprises a radially inwardly extending pin on said bushing engaging an upwardly inclined groove formed in the vertical post.

with a turning motion to turn said sleeve, said retaining means comprises an expansion spring on the vertical post operating between said bushing and a fixed member on the vertical post above said bushing.

13. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lowering said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its fully raised position for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, said means for turning said sleeve, comprising ratchet teeth formed on the upper end of said sleeve, a bushing vertically movable and rotatively mounted on the vertical post, means retaining said bushing in a lowered position, means for causing said bushing to be rotated through a portion of a revolution substantially equal to the distance between adjacent containers while the bushing is moving upwards, and ratchet teeth on the lower edge of said bushing to be engaged by the ratchet teeth of said sleeve as said sleeve approaches its fully up position after which further upward movement of said sleeve will cause said bushing to be raised with a turning motion to turn said sleeve, said bushing rotating means comprises a radially inwardly extending pin on said bushing engaging an upwardly inclined groove formed in the vertical post.

14. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lowering said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on

said sleeve and the vertical post effective while said sleeve is approaching its fully raised position for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, said means for turning said sleeve, comprising ratchet teeth formed on the upper end of said sleeve, a bushing vertically movable and rotatively mounted on the vertical post, means retaining said bushing in a lowered position, means for causing said bushing to be rotated through a portion of a revolution substantially equal to the distance between adjacent containers while the bushing is moving upwards, and ratchet teeth on the lower edge of said bushing to be engaged by the ratchet teeth of said sleeve as said sleeve approaches its fully up position after which further upward movement of said sleeve will cause said bushing to be raised with a turning motion to turn said sleeve, and means for retaining said sleeve against rotation during the major portion of its up and down movement.

15. In a watch cleaning machine having a hollow base and a vertical post extending centrally therefrom and a series of evenly spaced containers and a starting and stopping space between the first and last containers arranged in a circle about the vertical post, a tubular sleeve vertically slidable on the vertical post, means operated by a lift motor for raising and lower-

ing said sleeve, a circular plate mounted concentrically on said sleeve adjacent the top end thereof and arranged to engage over and close the open tops of certain of the containers in the lowered position of said sleeve, a spin motor mounted at a radial point on said plate and having a depending driven shaft, a basket for watch parts to be cleaned mounted on the lower end of said driven shaft to be successively extended into the containers in the various turned and lowered positions of said sleeve, means on said sleeve and the vertical post effective while said sleeve is approaching its full raised position and again moving away therefrom for turning said sleeve through that portion of a complete revolution corresponding to the spacing of said containers to shift said basket from axial alignment with one container into axial alignment with the adjacent container, a source of electrical energy, a main switch, a timer including a normally closed electrical switch, and a circuit connecting said source of electrical energy, said main switch, the switch of said timer and said lift motor in series to energize said lift motor to raise and lower said sleeve when said switches are closed, and a counterbalance connected to said means for raising and lowering said sleeve to smooth out the raising and lowering thereof.
